JOSEF WEIDENBACHER, OF AUGSBURG, GERMANY

PORTABLE SHED STRUCTURE

Application filed May 29, 1930, Serial No. 457,417, and in Germany November 20, 1928.

Present day shed buildings show various deficiencies. The solidly built type may have smooth walls which on the inside may be decorated in any desired manner, they are also heat and soundproof, but the cost of their erection is high owing to the long time it takes to erect them and the relatively expensive building material. Once erected they cannot be taken apart again and transported to any other place. The portable kind on the other hand take less time to erect, but they are neither heat nor soundproof. Nor are their inner walls of the desired smoothness; on the contrary, structural details which prevent a full utilization of the enclosed space remain visible everywhere.

The latter deficiencies of the cheaper and more common iron or wooden structures are particularly objectionable in cases where such sheds are intended to serve for the housing of exhibitions or for concerts and festivals, or as town halls, art galleries, meeting places, for indoor sports or gymnastics, swimming or other baths, or skating rinks. They are also liable to defects due to the formation of condense water. Sound insulation is also quite insufficient as there is no air cushion to deaden the noises penetrating from without or within.

The main object of this invention is to obviate the above-mentioned drawbacks and to provide a portable shed structure, the interior of which is adequately insulated with respect to heat and sound.

A further object is to provide a portable shed structure, wherein the upper parts of the inner rods and the cross rods are connected by a transparent material forming ceiling windows, so that the shed interior receives a sufficient amount of light.

For that purpose the portable shed structure, according to this invention, is composed of outer rods, inner rods, girders and cross bars arranged in such a way that they form together with the wall linings and the roof linings an air cushion adapted to act as an insulation with regard to the heat and sound transmission.

The portable shed structure made according to this invention may be also used for fair

structures, coach-houses, refrigerating chambers, station buildings, halls for airplanes and airships, ateliers, theaters and similar buildings, work shops of all kinds, for instance, those wherein a constant temperature must be maintained, mortuaries, hothouses, churches, temporary buildings used in warfare and in cases of emergency and so on.

Fig. 1 shows schematically one of the normal trusses used in the structure according to the invention;

Fig. 2 a truss with a somewhat differently shaped inner rod;

Figs. 3 and 4 show schematically cross section and ground plan of a shed church;

Fig. 5 a cross section of a shed (for instance a church) with lateral naves;

Fig. 6 is a top view of a central shed and

Fig. 7 is a schematical representation of a three nave shed of great span.

Fig. 8 is a cross section of a shed on a larger scale.

The hatched portions of the drawings represent the air cushion, dotted lines the glass skylight and the flat lines outer and inner walls, in section.

The substructure of the novel shed building consists of any desired number of iron trusses disposed in pairs opposite one another and at intervals one behind the other or, as in the case of a central shed, along the sides of a square, (as shown in Figs. 1, 2, 3, 5 and 7) of about the shape shown in Fig. 1, the angle α being selected with due regard to the destination and also the required height and span of the building. The novelty of the construction of the truss is in the first place to be found in the outlines of the truss (see Fig. 1, normal truss and Fig. 2, variety of same) the characteristic feature of which will here next be described.

The outer rods (*d*) are vertical and form also the substructure for the skin which may be fastened thereto directly or by means of intermedial rods; the skin being plates or slabs of metal or stone (slate, eternit or similar material).

The inner rods (*b*) of the truss are inclined towards the interior and lead in a straight (Fig. 1) or slightly broken line (Fig.

2) from their tracing points A and C through the roof to the crown. The lower part of these inner rods is not only supporting structure but also substructure for the inner walls 5 (A—D and G—C) which run parallel to the outer walls and may be made of light structure planks, such as the material known as cellotex. The part of the inner rods (B—E and B—F) which projects beyond the roof 10 is also substructure for the outer, steep glass skylights.

The horizontal intermedial rods D—G support also the inner skylight.

Truss rods H—E and F—J serve as sub- 15 structure of the flat roof, which roof may be made of the same material as the outer walls.

A shed according to this invention either with or without lateral naves (Figs. 2 and 5) may be advantageously used as a church.

20 If the spans are too great, two or more sheds may be combined in a way shown in Fig. 7. The inner intermediate rods *h* are coated on all sides with light planks, similarly to the interior walls (Fig. 7).

25 A number of wind-struts depending on the particular construction and the dimensions of the shed is inserted within the interior walls and obviously on the interior sides thereof, said wind-struts being arranged 10 in diagonals and in the vertical planes HD and GJ in diagonals crossing each other (Fig. 4).

The number and the distribution of the intermediate rods *c* depends on the dimensions of the shed, the employed trusses and the prescribed statical standardized regulations.

35 The following advantages are gained by the described disposition of walls and double 40 skylights.

The windowless smooth inner and outer walls are easily kept in good repair; the light streams evenly into the building from the top, heavy shadows are thereby avoided the 45 light rays (*f*) illuminate walls and floor evenly and brightly so that no portion of the interior lies in the shade.

Central sheds made according to this invention have a great amount of light. In 50 the modification shown in Fig. 6 the vertical projection of the upper light amounts to about 30% of the shed plan surface.

In winter the outer skylight in consequence of its steepness keeps free from snow and 55 never needs to be cleaned.

Inside the building the walls are perfectly smooth, none of the substructure being visible and the plates or slabs forming the inner and outer walls may be fixed to the substructure 60 without the use of expensive and complicated scaffolding as, starting from the bottom, by the aid of a simple flying scaffold they may easily be screwed or nailed on to the trusses (Fig. 3, *e*₁, *e*₂, *e*₃, *e*₄).

65 The smooth inner walls admit of any kind

of decorative treatment. Owing to their slant, dust cannot cling to the surface.

Foundations are necessary only for the tracing points of the trusses A, C, and so on; there is no need for foundation walls, which 70 circumstance cheapens the erection and is also of advantage in cases where the condition of the foundation soil is unsuitable. When a central hall is being built the trusses are placed along the sides of a square or a rectangle, as already mentioned. A central shed may be erected on as few as four tracing points of force (Fig. 6, A, B, C and D).

The layer of air between the inner and outer walls is continuous and of great depth consequently disturbing noises will effectively be stopped from penetrating into the structure; at the same time the air cushion will prevent music made inside the building to be 80 heard outside.

The acoustic properties of the structure will, because of the air cushion, also be excellent.

The air cushion will also prove to be a first 90 rate heat insulating means. This renders the structure equally suitable for use in tropical countries, for skating rinks or cold stores and as a heatable meeting place also for the taking of talking films, but especially for swimming baths, as there is no danger of the 95 structure getting damaged through condensed water.

None of the transportable sheds known in prior art have the advantages of a shed according to this invention, i. e. complete insulation with respect to heat and sound and completely smooth interior wall surfaces.

The novel shed structure may be erected in much less time than a shed of the solid type and although throughout cheap material may be used and its cost is about 40% less, it possesses the same valuable properties as those, viz: high stability, durability, heat and sound insulation, brightness and clearness of disposition of the interior space. In consequence the novel shed may be compared only to solid shed structures and not to the ordinary portable kind which are neither sound nor heat proof, have no smooth walls but on the contrary display everywhere their 105 unpleasing structural details.

In addition to the advantages already enumerated the novel shed offers the great advantage as against solid sheds, that they may be pulled apart and re-erected elsewhere 110 without loss of material.

Number and disposition of the rods (*c*) will in every case be ascertained by known 115 statical rules.

Claims:

1. A portable shed structure, comprising in combination, trusses with outer rods and inner rods having a greater slope than said outer rods, roof-girders having a slight inclination towards the horizontal, said inner 120

5 rods intersecting each other above the surfaces of intersection of said inner rods with said roof-girders and crossbars connecting said inner rods below the surfaces of intersection of said inner rods with said roof-girders.

10 2. A portable shed structure, comprising in combination, trusses with outer rods and inner rods having a greater slope than said outer rods, roof-girders having a slight inclination towards the horizontal, said inner rods intersecting each other above the surfaces of intersection of said inner rods with said roof-girders, cross-bars connecting said inner rods below the surfaces of intersection of said inner rods with said roof-girders and planks composing the walls and the roof of said shed, said planks forming an air cushion surrounding the interior of said shed.

15 3. A portable shed structure, comprising in combination, trusses with outer rods and inner rods having a greater slope than said outer rods, the lower ends of said inner rods being arranged closely to the lower ends of said outer rods, roof-girders having a slight inclination towards the horizontal, said inner rods intersecting each other above the surfaces of intersection of said inner rods with said roof-girders and crossbars connecting said inner rods below the surfaces of intersection of said inner rods with said roof-girders.

20 4. A portable shed structure, comprising in combination, trusses with outer rods and inner rods having a greater slope than said outer rods, roof-girders having a slight inclination towards the horizontal, said inner rods intersecting each other above the surfaces of intersection of said inner rods with said roof-girders, crossbars connecting said inner rods below the surfaces of intersection of said inner rods with said roof-girders and transparent means connected with the upper parts of said inner rods and said crossbars and forming an internal and an external skylight for the shed.

25 In testimony whereof I have affixed my signature.

JOSEF WEIDENBACHER.
